SURVEYING AND LEVELING INSTRUMENT

Dimond H. Loosli, Ashton, Idaho

Application May 14, 1937, Serial No. 142,702

4 Claims. (Cl. 33—73)

This invention is an instrument, in the nature of a level which may be used for surveying and indicating the rise and fall or height of terrain and among the objects of the invention are to provide a device or instrument of this character which can be readily carried from place to place, easily set up for use, and will at the same time have a high degree of accuracy in leveling operations.

The invention includes the provision of an improved target to be used in conjunction with the improved level.

The invention together with its objects and advantages will be best understood from a study of the following description taken in connection with the accompanying drawings wherein:—

Figure 1 is an elevational view of the instrument.

Figure 2 is a detail sectional view taken substantially on the line 2—2 of Figure 1.

Figure 3 is a detail view taken substantially on the line 3—3 of Figure 1.

Figure 4 is an enlarged detail view showing the manner of connecting fluid tubes or columns to the elbows at the opposite ends of a tubular arm.

Figure 5 is a plan view of the supporting head of a tripod and—

Figure 6 is a perspective view of one of the glass tubes or water columns.

Figure 7 is an elevational view illustrating the manner of using the level and target.

Figure 8 is a fragmentary elevational view of the target rod.

Figure 9 is a fragmentary side elevational view of the target rod with the target mounted thereon.

Figure 10 is a view taken at right angles to Fig. 9 and showing the face of the target.

Referring to the drawings by reference numerals it will be seen that in the preferred embodiment thereof the instrument includes a tripod or stand which in the present instance consists of a supporting head 5 having a tubular center portion 6 from which radiates flanges or wings 7. Secured to the wings 7 through the medium of bolts and wing nuts 8 are the upper ends of supporting legs 9 which are inclined at an angle corresponding to the angle of inclination of the outer edges of the wings 7.

The tubular or cylindrical body 6 of the head member 5 accommodates the bolt 10 equipped with a wing nut 11 and serving to clamp between the upper end of the head 5 and the head of the bolt a substantially U-shaped bracket 12.

A two part clamp 13 is provided and one end

of the jaws of the clamp are accommodated between the sides of the U-shaped member 12 and are apertured to receive a bolt 14 that extends through the apertured sides of the U-shaped bracket 12 and is equipped with a wing nut 15 which when screwed home on the bolt serves to draw the sides of the U-shaped member 12 and the ends of the jaws of the clamp 13 inwardly.

At the opposite end thereof the jaws of the clamp 13 are also apertured to accommodate a clamping bolt 16 equipped with a winged nut 17 and which cooperates with the bolt 14 to secure the jaws of the clamp about an elongated tubular member 18. In this connection, it will also be appreciated that the bolt 14 serves as a pivot for the clamp 13 and also serves to secure the tubular member 18 at the desired angular position of adjustment.

Threaded or otherwise provided on the respective opposite ends of the tube 18 are elbows 19. Threaded into the elbows 19 are nipples 20.

As clearly shown in Figure 4 each nipple 20 has threaded on its free end a packing nut 21 with which, in turn is threadedly engaged a gland nut 22 that cooperates with the packing nut 21 to secure at the free end of the nipple 20 a packing 23 through which one end of a glass or other transparent water tube or column 24 extends into the nipple 20.

Also, and as clearly shown in Figures 1 and 3, there is provided in the tubular member 18 adjacent one end thereof a manually operable valve 25.

For protecting the sight glasses 24 when the leveling instrument is not in use there is provided for each sight glass 24 a tubular protector casing 26, as shown in Fig. 4 and the casing 26 at one end is internally threaded to tread onto the upper end of a gland nut 22 as shown in said figure.

For use in conjunction with the leveling instrument there is provided a target indicated generally by the reference numeral 27.

Target 27 comprises a flat narrow elongated rod 28 provided on one face thereof with a series of graduations 29, the scale 29 being graduated in terms of inches and fractions thereof.

Slidable to the desired position of vertical adjustment on the rod 28 is a target plate 30 to the back of which is secured a U-shaped member 31 that embraces the rod 28. Carried by the member 31 intermediate its end is a spring 32 that has bearing contact with the back of the rod 27 and serves to frictionally secure the tar-

get plate 30 at the position of adjustment on the rod 27.

As shown in Fig. 10 the upper half of the face of target plate 30 is colored black while the lower half of said face is white to provide intermediate the upper and lower edges of the target plate a horizontal line 33 thereon to correspond to what may be the fluid surface level.

It will be understood that water is placed in 10 the tubular member 18 and the water columns or glass tubes 24 to an amount sufficient to provide, under normal conditions, a water level at a point coinciding with substantially half the length of 15 the glass tubes or water columns 24. It will be further noted that the tubes are opened at their 20 upper ends so that beads are formed in the glass at the top of the water columns therein and which beads are easily seen from quite a distance.

In the practical operation of leveling, the 25 instrument is set up, and the instrument may then be leveled by means of the two heights of fluid or water in the glasses 24. The use of the rod 28 with a target thereon is usual and customary in both leveling and surveying operations. After 30 the instrument and target have been set up, and the instrument leveled, the rodman will take the rod a predetermined distance away from the level and by sighting across the liquid so that the two surfaces will coincide with the mark or line 33 on the face of the target plate 30, this will give the 35 increase of height or the decrease, thus showing the variations in the contour of the terrain.

It will be further understood that when the instrument is in use valve 25 is in open condition. 40 When however the leveling instrument is being carried from place to place valve 25 is closed, and with the valve closed, and the instrument being carried at an angle of about 45° which is the usual angle of the instrument when being carried on the 45 shoulder of the rodman, the water in the tube above the valve cannot flow past the valve and the water below the valve cannot escape as it will become entrapped between the valve and the elbow on the lower end of the tubular rod. Thus in this manner the loss of water during transportation of the instrument is effectively guarded against.

Also with the protector tubes or shields 26 in 50 position the water tubes 24 will be protected against breaking.

Having thus described the invention, what is claimed as new is:—

1. A leveling instrument comprising a tripod, a clamp mounted on the tripod for pivotal move-

ment relative thereto, means for securing the clamp at the desired position of angular adjustment, a leveling tube secured by said clamp and extending at right angles from the tripod, elbows at the ends of the tube, packing and gland structures mounted upon said elbows, sight glasses having ends extending into said elbows through said gland and packing structures, and a valve mounted in said leveling tube adjacent one end of the latter.

2. A leveling instrument comprising a tripod including a head and inclined legs secured to said head, said head having a vertical axial opening therethrough, a U-shaped member disposed on said head, a bolt extending through said U-shaped member and the opening in said head and securing said U-shaped member to the head, a leveling tube, a clamp embracing said tube intermediate the ends of the latter, means pivotally connecting said clamp to said U-shaped member and including means for securing the clamp at the desired position of angular adjustment, elbows on the respective opposite ends of said tube, sight glasses mounted upon the upper ends of said elbows, and gland and packing assemblies securing the sight tubes to the elbows.

3. A leveling instrument comprising a tripod, a clamp mounted on the tripod for pivotal movement relative thereto, means for securing the clamp at the desired position of angular adjustment, a leveling tube secured by said clamp and extending at right angles from the tripod, elbows at the ends of the tube, packing and gland structures mounted upon said elbows, and sight glasses having ends extending into said elbows through said gland and packing structures, protector tubes for said sight glasses, and interengaging means on said protector tubes and on said packing and gland structures for releasably securing the protector tubes in position circumjacent the sight glasses.

4. In a leveling instrument of the character described, a leveling tube, elbows at the respective opposite ends of the tube, packing and gland structures respectively mounted upon said elbows, sight glasses having ends extending into said elbows through said gland and packing structures, said gland structures having threaded upper ends, and protector tubes for said sight glasses having internal threads at one end thereof for screw-threaded engagement with said upper ends of the gland structures.

DIMOND H. LOOSLI.
